(57) **CLAIM**

The ornamental design for a housing for use with a refill cartridge, as shown and described.

DESCRIPTION

FIG. 1 is a front perspective view of a housing for use with a refill cartridge in accordance with the present design; FIG. 2 is a right side elevational view thereof; FIG. 3 is a left side elevational view thereof; FIG. 4 is a front elevational view thereof; FIG. 5 is a rear elevational view thereof; FIG. 6 is a top view thereof; and, FIG. 7 is a bottom view thereof.

The broken lines shown in the drawings illustrate portions of the housing for use with a refill cartridge that form no part of the claimed design.

1 Claim, 7 Drawing Sheets
